HANDLE FOR KITCHEN UTENSILS, OR THE LIKE

Joseph Daniel Simon, Roslyn, Long Island, N.Y., assignor to Automatic Wire Goods Mfg. Co., Inc., Bronx, N.Y., a corporation of New York

Filed Nov. 19, 1964, Ser. No. 82,688

Term of patent 14 years

(Cl. D44—29)

FIG. 6

FIG. 5

FIG. 3

FIG. 2

FIG. 4

FIG. 1

FIG. 1 is a perspective view of a handle for kitchen utensils or the like showing my new design;

FIG. 2 is an elevational lengthwise view thereof;

FIG. 3 is the left end view of FIG. 2;

FIG. 4 is the right end view of FIG. 2;

FIG. 5 is a top plan view of FIG. 2;

FIG. 6 is a section taken at line 6—6 in FIG. 5.

The bottom surface of the handle is unornamented.

I claim:

The ornamental design for a handle for kitchen utensils or the like, substantially as shown and described.
